COMBINED NEWSPAPER AND MAGAZINE
DISPENSER

Bonnie J. Brown and Kenneth L. Brown,
Long Beach, Calif.

Application October 3, 1955, Serial No. 38,192

Term of patent 7 years

(Cl. D52—3)

FIG. 1.

FIG. 2.

We claim:

The ornamental design for a combined newspaper and magazine dispenser, substantially as shown.
